UNITED STATES PATENT OFFICE.

HARRY L. BEACH, OF COSHOCTON, OHIO.

DESIGN FOR A MATCH-BOX HOLDER.

59,402.

Specification for Design.

Patented Oct. 18, 1921.

Application filed March 12, 1921. Serial No. 451,830. Term of patent 7 years.

To all whom it may concern:

Be it known that I, HARRY L. BEACH, a citizen of the United States, residing at Coshocton, in the county of Coshocton and State of Ohio, have invented a new, original, and ornamental Design for a Match-Box Holder, of which the following is a specification.

Referring to the accompanying drawing—

I claim:

The ornamental design for a match box holder, substantially as shown.

In testimony that I claim the foregoing as my own, I have hereto affixed my signature.

HARRY L. BEACH.
